CONTAINER TOP CLOSURE

Eugene W. Skinner, Isaac L. Wilcox, and Robert F. Huntley, Fulton, N. Y., assignors to Oswego Falls Corporation, Fulton, N. Y., a corporation of New York

Application March 13, 1936, Serial No. 68,722

10 Claims. (Cl. 229—14)

This invention relates to containers used in the packaging of merchandise for retail, particularly food products. More particularly, the invention relates to those containers comprising an outer rigid casing of comparatively stiff paper-board, and which are provided with a liner bag of thin, flexible material having liquid and gas tight characteristics, such as Cellophane.

The invention has as an object, a container of the type referred to which is provided with a particularly economical and efficient top closure which is readily sealed to the container after the contents have been inserted in the same, and which may be readily and conveniently detached from the container and subsequent to the detachment used as a slip cover for the container until the contents therein have been completely used.

The invention consists in the novel features and in the combinations and constructions hereinafter set forth and claimed.

In describing this invention, reference is had to the accompanying drawings in which like characters designate corresponding parts in all the views.

Figure 1 is a side elevational view, partly in section, of a container embodying our invention.

Figure 2 is a fragmentary, exploded view with the container casing, liner bag, bag ring and top cover member arranged in their respective order for assembling.

Figure 3 is a fragmentary, sectional view of a container, similar to that shown in Figure 1, with a modified form of cover closure.

Figure 4 is a fragmentary, sectional, exploded view of the structure shown in Figure 3.

Figure 5 is a side elevational view, partly in section, of the top portion of a container embodying a modified form of our invention.

Figure 6 is a fragmentary, sectional, exploded view of the elements going to make the top closure in the modified form shown in Figure 5.

Figure 7 is a fragmentary, sectional view of a container, similar to that shown in Figure 1, illustrating still a further modification of our top closure.

Figure 8 is a fragmentary, sectional, exploded view of the structure shown in Figure 7.

Figure 9 is an enlarged, fragmentary, sectional view showing the detail construction of the upper left hand corner of Figure 1.

The invention comprises generally a tubular casing provided with a bottom closure, a ring member on the upper end of the casing, a bag of thin, flexible material arranged in the casing,

with the open end of the bag secured to said ring member, a cover member secured at its periphery to said ring member, one of said members having a portion depending in the casing, and said members acting as a detachable closure for the container upon severance of the bag from said ring member.

Referring to Figure 1, the casing 10 here shown is formed of comparatively rigid fibrous material, such as heavy paper-board, and is provided with a suitable bottom closure 11. The bottom closure may be also formed of paper-board, or may be metallic. As here shown, the bottom closure 11 is not integral with the casing 10, but is secured thereto by a crimping operation, as 15 at 12. A bag 13 of thin, flexible material is arranged within the casing 10, with the bottom of the bag resting upon the bottom closure 11, and the top of the bag extending to the open or top end of the casing 10. In Figure 1, the top 20 of the bag 13 extends over the top edge of the casing and a short distance down the outer surface of the casing.

This invention has to do particularly with the structure of the top closure for the container. 25 In Figure 1, the top closure consists of a ring member 15 formed with an outwardly flaring flange 16 and a depending portion 17 which is formed or provided with an inwardly extending rib or bead 18. The depending flange 17 is of 30 substantially the same diameter as the inner diameter of the casing 10, and the outwardly flaring top flange 16 overlaps the top edge of the bag which, in turn, overlaps the top edge of the casing 10 as previously explained, and the 35 flange 16 is crimped as shown in Figure 1, thus securing the liner bag 13 to the ring member 15 and the top portion of the casing. Also, preferably the inner surface of the casing 10, a short distance downwardly from the top edge, is provided with adhesive 19, the purpose of which is to seal or cement the side wall of the bag 13 to the side wall of the casing 10 at this point for reasons hereinafter explained.

A cover member 20 completes the closure structure in this instance. The cover 20 is substantially of conventional form. Both the ring member 15 and the cover 20 are formed of thin sheet metal, and the cover 20 is of a form conventional in ordinary tin can structures, being provided 40 with an outwardly flaring horizontal flange 21 which overlaps the previously crimped flange 16 of the ring member 15 and is tightly crimped and secured to it. This operation is substantially the same as that of crimping the cover 45

member of an ordinary tin can in place, inasmuch as the ring member 15 has been previously crimped securely to the top of the casing 10 and presents an end structure similar to the body portion of a tin can.

A circumferential inwardly extending groove 23 is formed in the casing 10 adjacent the upper end thereof and in alignment with the groove 18 formed in the ring member 15. The purpose of the grooves 23—18 is to form a knife guide. That is, to remove the top closure of the container, a knife is run around in the groove 23 which cuts through the casing 10 and also severs the upper end of the bag 13, the edge of the knife traveling in the groove 18 of the ring member 15. The top closure as a unit may be then readily removed from the container or casing 10, and the contents are available due to the fact that the liner bag has been severed simultaneously with the upper end of the casing. It will be observed that the bottom edge of the depending flange 17 is turned slightly inward as at 24. This is to permit the top closure to be more readily reinserted in the casing 10 and thus, the top closure becomes a detachable closure for use with the container until the contents have been completely consumed. Inasmuch as the Cellophane liner bag is attached to the inside wall of the casing 10 just below the groove 23, the top of the severed bag is held securely in place while the top closure is being used as a detachable put on and take off cover.

Referring to Figures 3 and 4, the top closure also consists of a ring member 29 positioned on the upper end of the casing 10, and being formed with a depending flange 17 and an upwardly extending cylindrical flange 30. The open end of the bag extends between the upper end of the casing 10 and the flange 17, and is crimped to the upper end of the flange 30, as at 31. The top closure is completed by the cover member 20 which is secured at its periphery to the ring 29 in the same manner as the cover 20 is secured to the ring member 15 in Figures 1 and 2. The flange 17 and the upper portion of the casing 10, in this instance, is not provided with a knife guide complementary to the grooves 18, 23, in Figures 1 and 2, inasmuch as the top portion of the Cellophane bag is exposed as at 32, and may accordingly be readily severed from the ring member 29 and thereafter, the top closure may be used as a detachable closure. The inner surface of the upper end portion of the casing 10 is preferably provided with adhesive 19, as in Figures 1 and 2.

Referring to Figures 5 and 6, the top closure also consists of a ring member 35 positioned on the upper end of the casing 10 and to which the upper end of the "Cellophane" bag is secured, and a cover member secured to the ring member and the casing. The ring member 35 is formed with a depending flange 36, and an outwardly flaring flange 37, the latter overlapping the top portion of the bag 13 and being crimped inwardly to tightly secure the end of the bag 13 to the ring member and to the top portion of the casing 10. The cover member 38 is generally of the form of that shown in Figures 1 and 2, except that the cylindrical portion 39 is of considerably greater depth and is provided with an inwardly extending circumferential groove or rib 40, corresponding to the rib 18 in the ring member 15, in Figures 1 and 2. The rib 40 is positioned just below the bottom edge of the depending flange 36 on the ring member 35, and the upper part of the casing 10 is likewise provided with the circumfer-

ential groove 41 with which the groove 40 is arranged in alignment.

As in the disclosure of Figures 1 and 2, the inner wall of the casing is preferably provided with a narrow band of suitable adhesive, or thermoplastic material, as at 19. It will be observed that the upper portion of the container and the bag 13 are severed between the knife grooves 40, 41, and the top closure may be then used as a "put on and take off" closure unit, until the contents have been entirely removed from the container.

In Figures 7 and 8, the cover member 50 is of the same structure as that disclosed in Figures 5 and 6. The ring member 51 is of fibrous material, and the upper end of the bag is secured thereto as by adhesive 52, and functions to hold the bag in place until the top closure has been completely attached to the container. This structure is likewise provided with the grooves 40, 41, to effect a knife guide in connection with severing the top of the container.

The use of this type of container for food products, such for example as coffee, is rapidly increasing, and it is necessary to have the container of such structure as to effect a gas-tight seam between the top closure and the open end of the bag 13, inasmuch as coffee, and other food products, generate a considerable amount of gas in aging, and which is preferably maintained at a predetermined pressure within the container, and the atmospheric air excluded from the interior of the container.

With the structure shown in Figures 1 to 6 inclusive, the container closure is substantially the same as that of a tin can structure. In instances where the container need not be quite so rigid, the metallic ring member may be substituted with the fibrous ring member 51, as shown in Figures 7 and 8. This type of container, while suitable for many commodities, is not so desirable for high gaseous commodities, such as coffee, as the seal is not so effective and will not withstand the pressures that the closures in Figures 1 to 6 will.

Attention is called to the fact that with our top closure structure, the can is very conveniently opened employing in such instances only an ordinary kitchen knife.

What we claim is:

1. A container comprising a tubular casing provided with a bottom closure, a bag of thin, flexible material arranged within the casing with the open end of the bag extending over the upper edge of the casing, a top closure for the container including a ring member securing the upper end of the bag to the upper edge of the casing, a cover member having its peripheral margin crimped into engagement with said ring member, said tubular casing being provided at its upper end with a peripheral recess adjacent the lower edge of the ring member, and one of said members being formed with a cylindrical portion having a complementary recess arranged in alignment with the recess in the casing, said recesses constituting a knife guide, whereby the top edge of the casing and the bag may be severed to effect opening of the container.

2. A container comprising a tubular casing provided with a bottom closure, a bag of thin, flexible material arranged within the casing, with the open end of the bag extending over the upper edge of the casing, a top closure for the container including a ring member formed with an outwardly flaring flange and a depending flange, said outwardly flaring flange overlapping the

- upper edge of the casing and securing the open end of the bag thereto, and said depending flange extending in the top portion of the bag and being provided with an inwardly extending groove, a 5 cover member provided with an outwardly flaring flange crimped over said flange of the ring member, and said casing being provided with an inwardly extending groove arranged in alignment with the groove of said ring member.
10. 3. A container comprising a tubular casing provided with a bottom closure, a liner bag of thin, flexible material arranged in the casing with the open end of the bag extending over the upper edge of the container, a top closure for the 15 container including a ring member U shaped in general cross section overlapping the upper end of said casing and said bag and securing said bag to said casing, a cover member provided with an outwardly flaring peripheral flange crimped into engagement with said ring and being provided with a cylindrical portion depending in said casing and being provided with an inwardly extending groove, and said casing being provided with an external peripheral recess in alignment with 20 said groove.
4. A container comprising a tubular casing provided with a bottom closure, a liner bag of thin, flexible material arranged in the casing with the open end of the bag extending over the upper edge of the casing, a ring member encircling the upper end of the casing and the overlapping portion of said bag and securing said bag to the upper end of the casing, a cover member formed with a cylindrical portion and an outwardly flaring flange encircling the top edge of the casing and said ring member and securing said elements together, a circumferential recess in the top portion of the casing immediately below said bag retaining ring, and a complementary 30 groove formed in the cylindrical portion of the cover member and arranged in alignment with the recess in the casing.
5. A container comprising a tubular casing provided with a bottom closure, a liner bag of thin, flexible material arranged in the casing with the open end of the bag extending over the upper edge of the casing, a ring member encircling the upper end of the casing and being secured the overlapping portion of said bag, a cover 40 member secured to said ring member and having a cylindrical portion depending in the casing, said depending portion being provided with a circumferential groove and a complementary circumferential groove arranged in the upper end of the casing in alignment with the groove in the cylindrical portion of the cover member.
6. A container comprising a tubular casing provided with a bottom closure, a ring member positioned on the upper end of said casing, a 45 cover member having an outwardly flaring circumferential flange crimped into engagement with said ring member, one of said members having a depending portion extending into the casing, a bag of thin, flexible material arranged in the casing with the open end of the bag extending between the inner surface of the casing and said depending portion, and being secured to said ring member, said members acting as a detachable closure for the container upon severance of the bag from said ring member.
7. A container comprising a tubular casing 5 provided with a bottom closure, a ring member positioned on the upper edge of the casing and being provided with a cylindrical portion depending in said casing, a bag of thin, flexible material arranged in the casing and being secured to said ring member, and a cover member having an outwardly flaring circumferential flange crimped into engagement with said ring member.
8. A container comprising a tubular casing 10 provided with a bottom closure, a ring member positioned on the upper edge of said casing and being provided with a cylindrical portion depending in said casing, and with an upwardly extending cylindrical portion, a bag of thin, flexible 15 material arranged in the casing with the open end of the bag extending between the inner side of the casing and said depending portion and encircling said upper cylindrical portion, and being secured to said ring member at its top edge, and a cover member secured at its periphery to the upper edge of said ring member.
9. A container comprising a tubular casing provided with a bottom closure, a ring member positioned on the upper edge of the casing, a bag 20 of thin, flexible material arranged in the casing with the open end of the bag secured to said ring member, a cover member having an outwardly flaring circumferential flange crimped into engagement with said ring member, and one 25 of said members having a portion depending in the casing below the upper edge thereof and operable to guide the top closure during application to the container after severance of the bag from said ring member.
10. A container comprising a tubular casing provided with a bottom closure, a liner bag of thin, flexible material arranged in the casing, a top closure for the container formed with a cylindrical portion encircled by the upper end of the casing and being provided with a circumferential groove extending inwardly toward the axis of the container, said casing being provided with a peripheral recess arranged in alignment with said groove in the flange of the top closure, and the open end of the bag being cemented to the inside of the casing below said peripheral recess.
